Term of patent 14 years

(Cl. D33—7)

Figure 1 is a front perspective view of a desk showing my design in closed position.

Figure 2 is a front perspective view of the pedestal in open position and showing the shelf member fully extended.

Figure 3 is a fragmentary front perspective view of the pedestal showing the top drawer member in fully extended position.

Figure 4 is a fragmentary side elevational view of the pedestal of Figure 3.

The side of the pedestal not shown is like the side shown while the back of the article is conventionally plain.

The dominant feature of this invention is the tambour type pedestal having a full length pull out, shelved tray which has a gradual forward and downward incline, this tray being combined with a small drawer above the tray, all as shown.

I claim:

The ornamental design for a desk as shown and described.
